UNITED STATES PATENT OFFICE

2,456,144

WATER HEATER

Clark M. Osterheld, Stoughton, Wis., assignor to
McGraw Electric Company, Elgin, Ill., a corporation of Delaware

Application November 30, 1946, Serial No. 713,336

3 Claims. (Cl. 219—39)

1

My invention relates to electric heaters, and particularly to electric water heaters for hot water tanks.

An object of my invention is to provide a relatively simple and novel form of electric tank water heater.

Another object of my invention is to provide an electric water-tank heater that shall rely on an integral, electric-insulating coating on the resistor for insulating the resistor from its support.

Another object of my invention is to provide an electric heater that shall embody a shroud portion in the supporting means for the resistor.

Other objects of my invention will either be apparent from a description of several forms of device embodying my invention or will be pointed out in the course of such description and be set forth in the appended claims.

In the drawings,

Figure 1 is a view in vertical section through an ordinary domestic water tank having associated therewith an electric heater embodying my invention.

Fig. 2 is a view in lateral section therethrough, taken on the line 2—2 of Fig. 1.

Fig. 3 is a fragmentary sectional view, taken on the line 3—3 of Fig. 2.

Fig. 4 is a fragmentary sectional view, taken on the line 4—4 of Fig. 2.

Fig. 5 is a fragmentary view of a water tank having associated therewith an electric water heater embodying my invention.

Fig. 6 is a view in section therethrough, taken on the line 6—6 of Fig. 5.

Fig. 7 is a fragmentary view of a hot water tank having a still further modification associated therewith.

Fig. 8 is a sectional view therethrough taken on the line 8—8 of Fig. 7.

Fig. 9 is a fragmentary view, in vertical section, of a modification.

Fig. 10 is a fragmentary view, in vertical section, of a still further modification, and

Fig. 11 is a fragmentary view of a resistor conductor which I may use with Fig. 10.

Referring first of all to Fig. 1 of the drawings, I have there shown a domestic hot water tank 11 having a lower closure member 13 with a cold water inlet pipe 15 associated therewith. I provide tank 11 with an upper closure member 17 having associated therewith a hot water outlet pipe 19. I provide also a mass 21 of heat insulating material such as mineral wool, which is held in proper operative position around tank 11 by an outer casing 23.

2

My electric heater, which is of the clamp-on type, is preferably positioned adjacent the lower end of tank 11 but I do not desire to be limited to the use of a single heater but may also provide an upper heater on the tank.

Heater 27 comprises a helically-wound resistor conductor 29 which is positioned within a substantially semi-cylindrical tube 31, this tube being provided with two sheath or shroud portions 33 and 35. I provide also a relatively small liner 37, which liner is of arcuate shape in cross section and which is adapted to be positioned between the heating conductor 29 and the outer wall of tank 11 substantially as shown in Fig. 3 of the drawings.

While I may use a metal such as brass or copper for the housing 27, as well as for the sheath portions 33 and 35, I may, and prefer, to use aluminum, which aluminum is provided on the inner surface of tubular portion 27 with an integral, inorganic, heat-conducting, high-temperature-resisting and electric-insulating coating which may be made or provided on the above mentioned portions according to the method set forth in U. S. Patent #1,526,127. I prefer to make the electric insulating coating have a thickness on the order of .001" but the thickness may vary between the limits of .0005" and .0015".

I provide the entire outer surface of the liner 37 with substantially the same kind of coating as hereinabove set forth in connection with members 27, 33 and 35.

While I may use a standard metallic resistance conductor for conductor 29 I do not desire to be limited thereto but may use an aluminum resistance conductor and may provide the entire outer surface of said resistance conductor with an electric insulating coating of substantially the same kind as hereinabove set forth in connection with members 31, 33, 35 and 37.

I may here point out that the dimensions of the tubular portion 31 and the thickness and width of liner 37 are so selected that the resistance conductor 29 will be held tightly between tubular member 27 and liner 37.

I hold the tubular resistance conductor supporting members 31, 33 and 35 in close clamping engagement around the outside of tank 11 as by providing sheaths 33 and 35 with laterally bent-out end portions 39 and 41, the length of tubular member 27 and of the sheaths 33 and 35 being made long enough so that a clamping bolt 43 may extend through holes in end portions 39 and 41 and be held by nuts 45, having engagement with a spring 47 positioned between end portion 41 and

nut 45. The use of a spring 47 will compensate for the greater expansion of an aluminum tubular clamping member around, say, an iron tank so that the heating unit will always be in close heat-transmitting engagement with the outer surface of tank 11.

Referring now to Figs. 5 and 6, I have there shown a plurality of tubular members 49 connected by an intermediate sheath 51 and having end sheaths 53 and 55 integral therewith, sheaths 51, 53 and 55 being adapted to be closely clamped against the outer surface of tank 11.

I provide also a liner 57 positioned between a resistance conductor 29 in tubular members 49 and the outside surface of tank 11. Substantially the same comments as hereinabove made in regard to the fit of conductor 29 between tubular member 27 and liners 37 and tank 11 apply also to the structure shown in Figs. 5 and 6.

The same comments as hereinabove made in connection with the use of an electric-insulating coating on the inner surface of tubular member 27 and on the outer surface of resistance conductor 29 apply also here.

I provide three bolts 43 extending between the spaced-apart end portions 61 and 63 of sheath portions 51, 53 and 55, each bolt 43 being provided with a nut 45 and a coil spring 47 between an end portion and nut 45.

Referring now to Figs. 7 and 8, I have there shown a tank 11 having securely clamped there-around a plurality of tubular members 65, having sheath portions 67, 69, 71 and 73 integral therewith, the shape of portions 65, 67, 69, 71 and 73 being such that tubular member 65 will extend vertically along the outer surface of tank 11. I provide a resistance conductor 29 in each tubular member 65 as well as a liner 75, the resistance conductor 29 and liner 75 being so dimensioned in regard to the substantially semi-cylindrical tubular portion 65 that resistance conductor 29 will be held tightly in its proper operative position within the tubular portion 65.

I may provide three sets of tubular members 65 spaced equi-distantly around the periphery of tank 11 and may clamp the upper ends of these tubular members 65 and the sheath portions 67, 69, 71 and 73 against the outer surface of tank 11 by a strap 77, while the lower ends are clamped by a strap 79. Both the upper and the lower straps 77 and 79 are tightly clamped against the outer surface of tank 11 by bolts 81 extending through end portions 83 and 85 of straps 77 and 79, a nut 87 being provided, as well as a coil spring 89, between the nut and portion 85 of the straps.

The thickness of tubular portions 27, 49 and 65 may be on the order of .035" and although I give a definite thickness I do not desire to be limited thereto since the thickness may vary between, say, the limits of .03" to .04", or may even be slightly larger.

Referring now to Fig. 9 I have there shown a modification of an electric heater embodying my invention and comprising a resistance conductor 91 which is wound first into helical form and is then flattened to substantially the flattened shape shown in Fig. 9. A thin liner 93 is located between the conductor 91 and the tank 11 and is housed in a tube 95 having sheath or shroud portions 97 and 99. The assembly of tubular member 95 is such that it will hold the conductor 91 and the liner 93 tightly against each other within it. Substantially the same means for holding the heater against the outside of the tank 11 as here-

inbefore described in connection with Figs. 1 to 3 may be used.

Referring now to Figs. 10 and 11, I have there shown still another form of electric heater embodying my invention. A preshaped resistance conductor 101 comprising a strip of resistance material provided with lateral slots extending alternately to opposite edges is bent to substantially channel-shape and a thin liner 103 is located between the inturned sides of resistor strip 101 and tank 11. A tube 105, having sheaths or shroud portions 107 and 109, holds the preshaped resistor within it and may be held around tank 11 by the same means shown in Figs. 1 to 3 inclusive.

While I may use ordinary metallic resistor material I may also use aluminum resistor material for resistors 91 and 101, which resistors may have coating over their outer surface of the kind and thickness as hereinbefore described in connection with resistor 29.

The thickness of walls 95 and 105, as well as of sheaths 97, 99, 107 and 109, may be on the order of .035" and the thickness of liners 93 and 103 may be on the order of .015", while the thickness of the electric-insulating coating thereon may be on the order of .001" and they may preferably consist of aluminum.

It will be evident that the use of sheath portions tightly engaging the outer surface of tank 11 provides a relatively large area for the flow of heat translated in the resistance conductors in the tubular portions so that the temperature gradient will be relatively small. One of the drawbacks of an internal electric heater has always been found to be the deposit of lime on the internal heater, particularly when the amount of heat per unit of area was relatively large, and in my novel construction no such high or large amount of heat per unit of area does flow so that there will be no tendency for the deposit of lime on the heater. This absence of deposit of lime is of course also because of the fact that the heater is not in engagement with the water which it is to heat.

Various modifications may be made in the device embodying my invention without departing from the spirit and scope thereof and I desire that all such modifications coming clearly within the scope of the appended claims shall be considered a part of my invention.

I claim as my invention:

1. An electric heater for a hot water tank comprising a corrugated strip adapted to be mounted against the outside surface of a tank, a relatively thin liner, of substantially semi-circular shape, in contact with the tank, a helically wound metallic resistor member in said corrugation engaging said liner and said corrugation and means for tightly clamping said corrugated strip against the tank and for clamping said metallic resistor member tightly between said corrugated strip and said liner and the outside surface of the tank, the entire outer surface of said metallic resistor member having thereon an inorganic, high-temperature-resisting, heat-conducting and electric-insulating coating.

2. An electric heater for a hot water tank comprising a corrugated metal strip adapted to be mounted against the outside surface of a tank, a relatively thin metal liner, of arcuate shape in lateral section in said corrugation in contact with the tank, a helically wound metallic resistor member in said corrugation engaging said liner and the inner surface of said corrugation and

means for tightly clamping said corrugated strip against a tank and for clamping said metallic resistor member tightly between said corrugated strip and said liner and the outside surface of a tank, the inner surface of said corrugation and the entire surface of said liner having thereon an inorganic, high-temperature-resisting, heat-conducting and electric-insulating coating.

3. The combination of claim 2 wherein said coated members comprise aluminum and said 10 coatings thereon comprise an oxidation product of aluminum.

CLARK M. OSTERHELD.
